UNITED STATES PATENT OFFICE

HARRY E. NORVIEL, OF ANDERSON, INDIANA, ASSIGNOR TO DELCO-REMY CORPORATION, OF ANDERSON, INDIANA, A CORPORATION OF DELAWARE

SWITCH

Application filed November 29, 1929. Serial No. 410,464.

This invention pertains to electric switches designed for the control of a plurality of circuits, and is particularly concerned with that type of switch mounted upon the lower end of a steering post of an automotive vehicle and adapted for controlling a number of circuits by a controller carried by the post.

It is an object of the instant invention to provide a switch of the class described that is simple in construction and compact in form.

It is a further object of the instant invention to provide a switch structure that is capable of selectively controlling circuits by both an axial and angular movement of parts of the switch structure.

It is a further object of the invention to provide a switch structure having a plurality of movable contacts, and in which axial movement of a part of the switch structure will control certain circuits irrespective of the angular position of said switch structure in controlling other circuits therethrough.

It is a further object of the instant invention to provide means for maintaining the contacts in engagement with a terminal support at the same time restraining one of the contact members from engagement with said terminal support.

Further objects and advantages of the present invention will be apparent from the following description, reference being had to the accompanying drawings, wherein a preferred embodiment of one form of the present invention is clearly shown.

In the drawings:

Fig. 1 is an elevational view of a steering post of an automotive vehicle provided with my improved switch structure, the same being shown in substantially vertical section.

Fig. 2 is a plan view of the switch back with a section through the casing supporting the same, substantially as indicated by the line and arrows 2-2 of Fig. 1.

Fig. 3 is a plan view of one of the contact plates contributing to the invention.

Fig. 4 is a vertical view of the same substantially as indicated by the line and arrows 4-4 of Fig. 3.

Fig. 5 is a face view of the driving mem-

ber supporting the contact plate of Figs. 3 and 4, with the same indicated thereon by dot-and-dash lines.

Figs. 6 and 7 are details of the horn contact member.

In the drawings, 20 refers to a position of the steering post which may be secured to the frame of the vehicle by the attaching lug 21 and bolt and nut device 22, and may include a number of control tubes 23 connected to control members 24 at the hub of the steering wheel 25. One of these control members 24 as 26 terminates at the hub of the wheel with a button 27 and extends beyond the lower end of the post 20 through the attaching flange 28 where it has driving engagement with the switch structure as will presently appear. In the instant invention the switch structure is enclosed in a housing 30 of cup form, the bottom 31 being secured to a U-shaped bracket 32 having attaching ears 33, secured to the flange 28 of the post 20, by the bolt and nut devices 34. The bottom 31 of the cup and the bracket 32 is centrally apertured and the casing is flanged at 35 to provide a sleeve fitting within the aperture of the bracket 31, which forms a bearing for the head 36 of a driving shaft 37 that is drivingly connected with the control member 26 by means of a pin 38 maintaining them in non-rotative relation.

Within the housing there is a dielectric driving plate 40 having a hub 41, provided with a bore 42 concentric therewith for receiving the shaft 37 that has a driving engagement therewith by means of the non-rounded head 36. Thus, driving engagement is provided between the dielectric member 40 and the push-pull controller 26. The member 40, as will be seen by reference to Figs. 1 and 5, is further provided with appointments including the raised central area or plateau 44 supporting the hub 41, which plateau is radially grooved at 45, 46, 47 and 48 providing driving engagement and one way mating relation with cooperating extensions 49, 50, 51 and 52 of a contact plate 53. A portion of the edge of the plate 40 is removed to provide the arcuate notch 54 that cooperates with a squirt or tongue 55 in the

bottom 31 of the housing, that acts as a stop or limiting means for rotation of the driving member relative to the case.

The contact plate 53 is of the general triangular formation exhibited in Fig. 3, and is of relatively open foraminous construction as illustrated. The plate is centrally apertured at 56 of sufficient dimension to be disposed over the hub 41 of the drive plate 40, and adjacent this aperture are located the extensions or squirts 49, 50, 51 and 52 which provide the driving engagement with the plate 40. At each apex of the triangular plate, the same is deformed into the contact points 57, 58 and 59, and portions of the plate between these contact points and the central aperture 56 are punched out as at 60, 61 and 62 so that each of the contact points 57, 58 and 59 will be joined to the main body 20 of the plate by a pair of integrally formed diverging, resilient or flexible arms 63 and 64. Each pair of diverging arms 63 and 64 are bent out of the plane of the main portion of the plate as indicated at 65 in Fig. 4 for 25 a purpose which will presently appear, as illustrated in Fig. 1.

The hub 41 of the dielectric member also supports a second contact member 70 as illustrated in detail in Figs. 6 and 7. This 30 contact member comprises a washer like ring 71 of resilient metal providing a central aperture 72 for disposition over the hub 41, and one or more lateral extensions 73, laterally flexed at 74 as illustrated in the detailed 35 showing provide contact engaging portions.

In assembling these elements with the driving member, a contact urging spring 80 is placed upon the driving member 40 so as to be disposed about the raised portion 44, 45 and the contact member 53 is then passed over the hub with the extensions 49, 50, 51 and 52 disposed for engagement within the radial slots 45, 46, 47 and 48 respectively. This will bring the contact points 57, 58 and 59 in direct engagement with portions of the spring 80, for a purpose presently to appear. The contact member 70 is then placed over the hub and a second spring 81 is disposed thereagainst to engage the ring portion 71 50 and force the same into engagement with the contact member 53. This spring also tends to maintain the plate 53 in driving engagement with the plate 40. A switch back 85 is then placed upon the casing 30 to close off the same, and is retained in such position by the tongues 86 peripherally arranged about the casing 30 and bent against the back side thereof as illustrated in Figs. 1 and 2.

This switch back provides a plurality of 60 fixed contacts 87 arranged in concentric form about an aperture 88 of the switch back, and adapted for cooperation with one or another of the various contact points 57, 58 and 59 of the contact plate 53. The fixed contacts 87 65 may terminate exterior of the switch back in

terminal clips 89 as illustrated in Fig. 1. Concentric with the aperture 88 the switch back also provides a contact ring 90 that is arranged for engagement by the extensions 73 of the contact plate 70 and may terminate on the rear side of the switch back in a terminal clip 91. Concentric with the aperture 88 and within the ring 90, the switch back is provided with a countersink 92 within which may be seated the spring 81.

It will be understood, of course, that when the switch back 85 is secured to the housing 30, that the switch structure will be confined between it and the bottom 31 of the said housing. The springs 80 and 81 will then be under compression so that the contact plates 53 and 70 will be maintained in disposition upon the hub 41 with the driving positions of the plate 40 in mating engagement with the reciprocal positions of the plate 53, and so that the spring 80 will urge the contact points of the plate 53 individually into engagement with the switch back 85. These facts will obtain throughout the normal disposition of forces within the switch structure. The construction of the contact plate 53 is such as to provide the contact points 57, 58 and 59 as being independently flexible relative to the body of the plate so that when mounted upon the dielectric member 40 and subjected to the urging of the spring forces described, that the contact support assembly will readily assume the position illustrated in Fig. 1. The contact points of the plate 53 will each normally be in engagement with the switch back 85, and the contact member 70 will be out of engagement with any portion of the switch back.

However, the structure is such that the driving member 40 may be moved to any angular position permitted by the stop provisions 54 and 55, and at the same time will be permissible of axial movement independent of any of said angular positions. That is, the contact assembly may be moved to any of the angular positions, and irrespective of that angular position may be moved axially without affecting the angular position of said movement.

In main the spring 81 is a return spring for the contact member 70 so as to move it away from the contact ring 90 when pressure upon the control member 27 is released, but it may, however, contribute to the movement of the entire contact actuating assembly upon such release. The spring 80 performs a dual function, in that, it not only maintains the contact points 57, 58 and 59, in engagement with the switch back, but also functions to return the contact assembly to the position of rest as exhibited in Fig. 1, directly that pressure is released upon the control member 27. This aids in withdrawing the contact member 70 from the contact ring 90. This spring force tends to urge the driving member 40

and the contact points of the plate 53 against opposing walls of the switch housing.

While the form of embodiment of the present invention as herein disclosed, constitutes a preferred form, it is to be understood that other forms might be adopted, all coming within the scope of the claims which follow.

What is claimed is as follows:

1. A circuit controller adapted for use on an automotive vehicle, comprising in combination, a steering post providing a depressible and rotatable control member operable therethrough, a switch device secured to the end of said post and adapted for operation by said controller, said switch device comprising, a dielectric driving member loosely supporting a pair of contact members cooperable with a terminal plate, and means engaging said terminal plate, driving member and contact members permitting rotation and depression of said control member. 55
2. In a switch for use with automotive vehicles the combination comprising, a switch case and a dielectric driving member therein, said case and member being centrally apertured for reception of the drive shaft, a pair of contact members drivingly engaging said dielectric member and in cooperable engagement with contacts supported by a switch back closing said case, one of said fixed contacts being a ring concentric with said drive shaft and disposed for engagement with one of said contact members upon depression of said shaft. 65
3. In a switch of the class described, the combination comprising, a cup-shaped switch housing providing a central aperture in the bottom thereof, a dielectric driving member within the housing journaled for movement concentric with said case aperture, and providing a plurality of radial grooves upon the inner face thereof, a pair of contact plates concentric with said journal portion one of said plates having axial extensions receivable by the grooves of said dielectric member, a switch back closing said casing and providing fixed contacts in cooperable engagement with each of said contact members, means urging the contact plates against the dielectric member, and means urging one of the contact members against the switch back. 105
4. In a switch of the class described, the combination comprising, a cup-shaped switch housing providing a central aperture in the bottom thereof, a dielectric driving member within the housing journaled for movement concentric with said case aperture, a shaft having a bearing in the aperture of said case and drivingly engaging said dielectric member, a pair of contact members drivingly supported by said dielectric member, and a switch back closing said housing and providing terminal members for cooperative engagement with each of said contact members, means about said shaft urging both of said contacts into engagement with said dielectric member, and means disposed between said dielectric member and one of said contact members urging the latter into engagement with said switch back, said dielectric member being depressible for actuation of one of said contact members and rotatable for actuation of another of said contact members. 115
5. In a switch of the class described, the combination comprising, a cup-shaped switch housing providing a central aperture in the bottom thereof, a dielectric driving member within the housing journaled for movement concentric with said case aperture, and providing a hub portion upon which is disposed a pair of contact members, one of said members having driving engagement with said dielectric member, a switch back providing terminal members in cooperative engagement with each of said contact members, and means disposed against the switch back for urging both of said contact members upon said dielectric member, and means disposed between the dielectric member and one of said contact members maintaining the same in engagement with said switch back. 125
6. In a switch of the class described, the combination comprising, a cup-shaped switch housing providing a central aperture in the bottom thereof, a dielectric driving member within the housing journaled for movement concentric with said case aperture, a shaft journaled within the aperture of said case and having nonrotatable engagement with said dielectric member, contact means carried by said dielectric member, one of said contact means having engagement for rotation with said dielectric member, while another of said means may move axially independent of the same, a switch back closing the casing and providing terminal members in cooperable engagement for each of said contact means, and a rotatable and depressible controller connected with the shaft for selectively controlling both of said contact means. 135
7. In a switch, the combination comprising, a housing, a dielectric driving member within the housing and actuatable from without the same, said dielectric member providing a hub about which is disposed a pair of contact members, one of said contact members having driving engagement with said dielectric member, terminals supported for cooperative engagement with one or the other of said contact members, means urging one of said contact members away from one or more of said terminal members, and means for urging the other of said contact members into engagement with others of said terminal members. 145
8. In a switch, the combination comprising, a housing, a dielectric driving member within the housing and actuatable from without the same, into a plurality of axial and an-

gular positions, said dielectric member providing a hub portion and radial slots therefrom upon one face thereof, a pair of contact members carried by said hub portion, one of said contact members having provisions for engaging the slots of said dielectric member to be rotatable therewith, a closure for the switch case providing a plurality of contacts and supporting means urging the contacts upon the hub and into engagement with said dielectric member.

9. In a switch, the combination comprising, a housing, a dielectric driving member within the housing and actuatable from without the same, into a plurality of axial and angular positions, said dielectric member providing a hub portion and radial slots therefrom upon one face thereof, a pair of contact members carried by said hub portion, one of said contact members having provisions for engaging the slots of said dielectric member to be rotatable therewith, a closure for the switch case providing a plurality of contacts and supporting means urging the contacts upon the hub and into engagement with said dielectric member, and means interposed between one of the contact plates and said dielectric member maintaining engagement of said contact member with the closure member.

10. In a switch, the combination comprising, a housing, a dielectric driving member within the housing and actuatable from without the same, said dielectric member providing a hub portion receiving a pair of contact members, one of said contact members having driving engagement with said dielectric member and providing a plurality of resiliently supported contact points, a switch back for said housing providing a plurality of contacts, some engageable with each of said contact members, means concentric with the hub and engaging the switch back for maintaining the contact members upon said dielectric member, and means disposed against the contact points maintaining them in engagement with said switch back, said dielectric member being rotatable for controlling the position of said switch points and also being depreable for controlling circuits through the other of said contact members.

11. In an electric switch, the combination comprising, a casing, a dielectric driving member within the same, said driving member and case being coaxially apertured for the reception of a driving shaft, which shaft is journaled for rotation and axial movement through the case aperture and is non-rotatably associated with said dielectric member, said dielectric member having a hub portion supporting a pair of contact members and maintaining them in insulated relation with respect to said shaft, one of said contact members having driving engagement with said dielectric member, a

closure for said case supporting a plurality of contacts, some of which are cooperable with each of said contact members, means maintaining one of said contact members in engageable relation with some of said contacts, and means urging the other of said contact members out of engagement with any of said contacts, and means adapted for causing one of said contact members to engage a fixed contact irrespective of the contact engagement of said other contact member.

12. In an electric switch the combination comprising, a driving member having a hub portion and radially spaced slots, a contact plate disposed about said hub and having extensions providing a driving engagement with said driving member, means enclosing the driving member and contact plate, and means disposed between the contact plate and driving member urging the contact plate and driving member into engagement with opposed parts of the enclosing means.

13. In an electric switch the combination comprising, a driving member journaled for rotation and for axial movement relative to a switch back, said driving member supporting a contact plate in driving engagement therewith, and normally engaging the switch back irrespective of the rotation of said driving member.

14. In an electric switch the combination comprising, a driving member supported for both axial and angular movement with respect to a switch back, a pair of contact members supported by said driving member, one of said contact members being capable of rotation with said driving member, and the second of said contact members being axially movable with said driving member irrespective of the angular movement of said member.

15. In an electric switch, a contact support assembly comprising in combination, a dielectric driving member providing a hub, a contact plate carried by said hub and having interfitting engagement with parts of said driving member whereby said plate will be rotated upon rotation of the driving member, means retaining the contact member upon the driving member, and means tending to deflect parts of the contact plate away from the driving member.

16. In an electric switch, a contact support assembly comprising in combination, a driving member, a contact plate drivingly supported by said member, said plate being of foraminous construction and providing a plurality of contact points, each supported by a pair of converging resilient arms.

17. In an electric switch, a contact support assembly comprising in combination, a driving member, a contact plate drivingly supported by said member, and providing contact points, each of said points being integrally joined by diverging arms to the body

of said plate, whereby said points will be capable of lateral movement relative to the body of said plate.

18. In an electric switch, a contact support assembly comprising in combination, a driving member, a contact plate drivingly supported by said member, said contact plate being of triangular form and of foraminous construction providing a contact point at each apex of said triangular plate, and joined thereto by a pair of diverging resilient arms, whereby said contact points may be flexed relative to the body of said plate.

19. In an electric switch the combination comprising, a casing, a driving plate mounted for axial and angular movement within the casing and supporting contact members, means restraining one of said contact members in open circuit and for retaining one of said contact members in driving engagement with said plate, and means urging another of said contact members into engagement with a part of said casing, said contact urging means permitting axial movement of said driving member as well as engagement of said first contact member, and means operably connected with said drive plate for both axial and angular movement of the same.

In testimony whereof I hereto affix my signature.

HARRY E. NORVIEL.
